TRAIN-CONTROL SYSTEM.

Application filed June 7, 1922. Serial No. 566,565.

This invention relates to a train control system and more particularly to a system for automatically controlling the movement of cars, trains or the like responsive to track or roadside conditions.

The principal objects of the present invention comprehend the provision of a novel train control system in which the companion train and track apparatus are correlated to effect a very sensitive inertialess system adaptable for instantaneous operation and instant response to roadside conditions and especially serviceable for fast moving vehicles and trains.

To the accomplishment of the foregoing and such other objects as may hereinafter appear, my invention consists in the elements and their relation one to the other, as herein-after particularly described and sought to be defined in the claims, reference being had to the accompanying drawings, which show preferred embodiments of my invention, and in which:

Figure 1 is a perspective view of the vehicle and roadside apparatus.

Figure 2 is a diagrammatic view of the vehicle circuits and the roadside magnetic mechanism cooperating therewith, these parts being shown under clear track conditions,

Figure 2^a is a graphical view of the characteristic of the vehicle circuits shown in Figure 2,

Figure 3 is a view showing the track apparatus,

Figure 4 is a diagrammatic view of a modified form of the vehicle circuits and the track mechanism associated therewith, these parts being shown under danger track conditions,

Figure 4^a is a graphical representation of the characteristic of the circuits shown in Figure 4, and

Figure 5 is a view of a modified system.

Referring now more in detail to Figures 1 and 2 of the drawings, my invention broadly comprehends the provision of a train control system in which electrical train circuits are magnetically influenced by track

mechanism preferably intermittently operative at predetermined times, the vehicle and track mechanisms cooperating to effect a

very sensitive and inertialess train control apparatus. More specifically, my present invention comprehends the provision of a train circuit including a thermo-ionic device arranged to be magnetically influenced by track mechanism depending upon roadside conditions for modifying the characteristics of the circuit responsive to changing track conditions. As shown in Figure 2, the train control circuit is under the control of an electron discharge device or thermo-ionic element in the form of a magnetron generally designated as M, the magnetron comprising a vacuous vessel or tube 10 provided with the cathode in the form of a straight filament 11 and a cylindrical anode 12 symmetrically encircling the cathode, the filament 11 being provided with the sealed terminals 13 and 14 and the anode 12 being provided with the sealed terminal 15, and encircling the tube 10 symmetrically with the cathode and anode I provide the two solenoids 16 and 17 arranged, as will be detailed hereinafter, in independent circuits, the said solenoids being provided for selective control of the activity of the thermo-ionic element M. In the diagrammatic illustration in Figure 2 the solenoids 16 and 17 for purposes of clarity have been shown arranged to the sides of the tube 10, but it will be understood that the actual construction comprises a symmetrical arrangement of these solenoids encircling and surrounding the tube, the solenoids being coaxial with the anode and cathode of the tube.

For heating the filament or cathode 11 to obtain the desired emission of electrons, the terminals 13 and 14 of the cathode are connected to a glow circuit including the battery or other source of energy 18, the opposite poles of which are connected to the terminals 13 and 14 as by means of the conductors 19 and 20. As is well known, upon heating the filament 11 by means of this glow circuit there will be an emission of electrons from the filament 11 to the anode 12 and upon closing a circuit including the anode and cathode a current will be established therethrough.

The thermo-ionic element M is arranged in a train circuit, selective activity of the element M being provided for controlling

the said train circuit. The train circuit ising the anode 12, and the current in the out-connected across the cathode and anode of the element M, the said circuit including the solenoid 21 of a relay, one terminal of the 5 said solenoid 21 being connected by means of a conductor 22 to the anode terminal 15, the other terminal of the solenoid 21 being connected by means of a conductor 23 to the solenoid 17 which in turn is connected by 10 means of a conductor 24 to one terminal of a battery or other source of energy 25, the other terminal of the battery being in turn connected by means of a conductor 26 to the cathode terminal 13. The solenoid 21 of the 15 relay, therefore, is connected in series with the solenoid 17 of the thermo-ionic element and across the cathode and anode terminals of the thermo-ionic device.

For energizing the solenoid 16 of the 20 thermo-ionic element M there is provided the battery or other source of energy 27 connected to one terminal of the solenoid 16 as by means of conductor 28, the other terminal of the solenoid 16 being connected to 25 the other terminal of the battery 27 by means of a conductor 29, a rheostat 30 in series therewith and a conductor 31^a. The rheostat 30 is provided for obtaining the desired energization of the solenoid 16 to effect 30 a predetermined magnetic influence on the thermo-ionic device M, as will become clearer presently.

As is known, in the absence of any magnetic influence on the magnetron M, the 25 magnetron will be open and a current will flow through the controlled relay circuit for energizing the said circuit to effect the operation of the relay magnet 21. It is also known that when the magnetron 40 M is subjected to the influence of the magnetic field above a predetermined or critical magnitude, the electron flow between the cathode and anode will be interrupted for closing the magnetron and deenergizing 45 the relay magnet 21. This phenomenon is graphically illustrated in Fig. 2^a of the drawings, this figure representing the operating characteristics of the magnetron under the influence of the magnetic field, the 50 strength of the magnetic field being represented by the abscissæ and the strength of the current in the output or controlled relay circuit by the ordinates, the curve EDAB depicting the characteristics of the magnetron and controlled circuit. If the 55 strength of the magnetic field influencing the magnetron is less than the abscissa represented as CD, the electrons emitted from the cathode impinge uninterruptedly upon 60 the anode and the current in the controlled circuit will be a maximum, as represented by the ordinate XC. If, however, the strength of the magnetic field exceeds the critical point represented as D, the electrons 65 will be diverted and prevented from reach-

put or controlled circuit will constantly fall without lag or inertia to a value as represented by the part of the curve AB. From this it will be seen that the magnetron may 70 be controlled by controlling in a predetermined manner the magnetic influence to which it is subjected.

For controlling the operation of the magnetron and the condition of the output circuit in accordance with my invention, I provide means for producing opposed magnetic fields influencing the magnetron, the said opposed magnetic fields having a given resultant magnitude, which magnitude is selectively changed and reestablished to produce different conditions of operation. To this end the solenoids 16 and 17 heretofore referred to are so wound and arranged on the magnetron tube 10 as to produce magnetic fields in opposition, as indicated by the arrows in Fig. 2, the strength of the opposing magnetic fields being so predetermined that the magnetic field produced by the solenoid 16 when acting alone is effective 80 for establishing one condition of operation and the strength of the resultant of both magnetic fields when acting in opposition is effective for producing a different condition 85 of operation. These predetermined magnitudes are graphically illustrated in Fig. 2^a of the drawings, the strength of the magnetic field due to the solenoid 16 being indicated by the arrowed line M', the value 90 of this field being greater than the critical value of the curve EDAB, this magnetic field being therefore sufficient when acting alone to close the magnetron and deenergize the controlled relay circuit; and the strength of the opposing magnetic field produced by the solenoid 17 is indicated by the opposing arrowed line O, the inter-reaction of the fields M' and O being such as to produce a resultant field indicated by the arrowed line R, this resultant being of a value less than the critical value of the curve and insufficient to disturb the open magnetron M and the energized relay circuit, the value of the current in the circuit being represented by the asterisk on the curve, Fig. 2^a. With this arrangement the high tension current passing through the output circuit of the magnetron is at its maximum and quite able, by means of the relay 21, to operate additional train circuits for controlling the movement 105 of the train.

For controlling the movement of the train the relay 21 is provided with the armature 31 arranged in a circuit including the battery 32, the brake mechanism 33 and the contact element 34, normal energization of the relay 21 effecting the closing of this circuit, preventing an operation of the brake mechanism 33. If, however, the relay 21 is 110 deenergized, this circuit will be opened, ef-

125

130

fecting the application of the brakes by the brake mechanism 33.

In the normal operation, therefore, of the train apparatus, the magnetron M is open 5 for energization of the relay 21 which in turn closes the brake circuit to permit the train to run under clear conditions, the thermo-ionic element M being normally under such magnetic influence as to permit 10 a change in the control of the train circuits upon an unbalancing magnetic influence in a track mechanism.

For producing the different operations of the magnetron and controlled circuit, the 15 resultant magnetic field is modified and re-established, the modification of the resultant field rendering the magnetron inactive and the re-establishing of the field effecting the re-establishing of the activity of the 20 magnetron. These results may be accomplished in a number of ways, and in the construction exemplified in Figs. 1 and 2, I provide means in the form of track mechanism neutralizing the effect of the opposing 25 magnetic field when the relay or output circuit is to be deenergized, and means for re-establishing this effect when re-energization of the circuit is desired. For magnetically controlling the magnetron M by the track 30 mechanism there is provided a track magnet m which preferably comprises a solenoid 35 provided with an hermetically closed brass tube 36 in which a permanent magnet 37 is arranged for ascending and descending 35 movement, the said permanent magnet 37 having a polarity the same as the polarity of the coil 35, as clearly shown in Figure 2 of the drawings, this to the end of providing a construction in which the magnetization 40 of the coil 35 helps to retain the permanent magnetism of the magnet 37. The construction of the track magnet m is preferably such that when the coil 35 is deenergized the magnet 37 is moved to its uppermost 45 position in the tube 36, a spring 38 being provided for this purpose, and when the magnet 37 is in this uppermost position the magnetron tube M in being moved over the magnet m will come under the influence of 50 the magnetic field of the said magnet 37. When the coil 35 is energized, however, the magnet 37 will be sucked into the coil 35 against the action of the spring 38, this being 55 shown in Figure 2 of the drawings, and with the magnet 37 in this position the magnetron M will move over the magnet m uninfluenced thereby.

The track magnet m and more specifically the magnet core 37 provides a magnetic field 60 of a polarity such as to aid the magnetic field provided by the solenoid 16 or, conversely, to oppose or neutralize the magnetic field provided by the coil 17. When the magnetron M is moved over the track 65 magnet m the influence of the track magnet

is such that the effect of the opposing magnetic field O of coil 17 is neutralized so that the main field M' alone is active for closing the magnetron and deenergizing the relay circuit. This magnetic influence need 70 be only momentary in the quick passage of the train and the magnetron M over the track magnet m for the deenergizing of the circuit to the control relay 21 deenergizes the coil 17 with the result that after the 75 magnetron M has passed beyond the track magnet m, the magnetization of the solenoid 16 is predominant and without opposition. In this way a permanent closing or "blowing out" of the magnetron M may be effected 80 instantaneously and by subjecting the magnetron M to momentary influence only of the magnet m.

With the construction thus far described it will be apparent that with clear track 85 conditions ahead the track magnet coil 35 will be energized to cause the core 37 to assume the position shown in Figure 2 of the drawings, the train circuits when moving past the track magnet being uninfluenced and retaining clear conditions on the vehicle. With danger conditions ahead, however, the track magnet coil 35 will be deenergized, bringing the magnetron M under the influence of the magnet core 37 to 90 effect a sudden and permanent closing of the magnetron and its circuit for opening the braking circuit to effect application of the brakes.

After the application of the brakes the 100 magnetron tube M may again be set into activity and to this end there is provided shunted across the elements of the thermo-ionic device a normally open circuit including the conductor 39 connected to the anode terminal 15, normally open switch 40, resistance 41, and conductor 42 connected to the cathode terminal 13. Upon closing the switch 40 it will be apparent that current will flow from the battery 25 through conductors 26 and 42, through resistance 41, switch 40, conductor 39, conductor 22, relay 21, conductor 23 and solenoid 17, the solenoid being thus energized for setting up a magnetic field in opposition to the magnetic 110 field of solenoid 16 to bring the magnetic influence to the point on the curve ED (Figure 2a,) designated by the asterisk (*), this magnetic influence being insufficient, as heretofore described, to retard the electrons 115 from reaching the anode 12, the magnetron tube M being thus reopened and set into activity for releasing of the brakes.

In the preferred construction of my system I provide two track magnets arranged 125 in succession before the entrance to each block, the first track magnet being used for closing the magnetron and the second one for reopening it, the arrangement of the parts permitting impressing upon the train 130

the clear, caution and danger track conditions. This is shown in Figures 1 and 3 of the drawings, and referring to these figures, arranged in each block such as E and F 5 there are provided the two track magnets m and m' each adapted for cooperation with the magnetron M and the train circuits carried by a vehicle 43. The track magnet m' (see Figure 3) also comprises a coil 44 having a non-magnetic tube such as a brass tube 45 in which is arranged a permanent magnet 46 adapted for ascending and descending movement in the tube 45, the polarity of the permanent magnet 46 being the same as 10 the polarity of the coil 44, as clearly shown in Figure 3 of the drawings. The polarity of the magnetic elements of magnet m' , however, is opposite to the polarity of the magnetic elements of the magnet m , this to 15 the end of influencing the train magnetron M in opposite manners. The track magnet m' is, furthermore, so constructed that the magnet core 46 assumes the descended gravitated position shown in full lines in Figure 20 25 when the coil 44 is deenergized, the magnet core 46, when the coil 44 is energized, being caused to assume the uppermost position in the tube 45, as shown by the dotted line position in Figure 3 of the drawings.

With this construction and arrangement 30 of the track magnets m and m' it will be apparent that if the magnetron M has been closed by moving under the influence of the track magnet m with the magnetic field of 35 the track magnet m aiding the magnetic field of coil 16, the magnetron may be reopened by energizing the track magnet m' and bringing the magnetron M under the influence of the magnetic field provided by the 40 core 46 in ascended position, this latter magnetic field opposing the magnetic field of coil 16 to an extent such that the resultant magnetic field is less than the critical value necessary to retain the magnetron M extinguished. The magnetron M will be therefore 45 momentarily influenced to cause a reopening of the same and an energization of its solenoid 17, energization of this solenoid providing the sustained magnetic opposition 50 to the magnetic field of coil 16, the magnetron tube being thus reopened permanently by the momentary influence of the track magnet m' .

With this construction clear, caution and 55 danger track conditions may be impressed upon the vehicle in the following manner:

1. Clear track conditions.

For clear track conditions the track magnet m will be energized and the track magnet m' will be deenergized to effect the positioning of the magnet cores as shown in 60 Figure 3 of the drawings, and in the block F of Figure 1 of the drawings. With the 65 parts assuming these positions the magne-

tron M, which in the normal operation of the train, is opened, will be uninfluenced by either the magnet m or m' and will pass the control track stations without any change impressed or imposed upon the train apparatus, the train therefore continuing to run "clear".

2. Caution track conditions.

For caution track conditions the magnet 75 m will be deenergized and the magnet m' energized, both the cores 37 and 46 assuming the uppermost and dotted line positions shown in Figure 3 of the drawings. With the parts assuming these positions the magnetron M in passing over the track magnet m , will be closed and the vehicle brakes applied, and the magnetron M after passing the succeeding track magnet m' , will be reopened to effect the releasing of the brakes, 80 service application of the brakes being thus provided for.

3. Danger track conditions.

With a vehicle or train in the next block, 90 the danger track conditions will be translated to the magnets m and m' , both magnets being deenergized, the core 37 of magnet m being in its ascended dotted line position (Figure 3) and the magnet core 46 being in 95 its descended full line position (Figure 3). With the parts assuming these positions the magnetron M, in moving over the magnet m , will be closed, and the magnetron in passing the magnet m' will be uninfluenced, the closing of the magnetron M being thereby maintained for the complete application of the brakes and the stopping of the train. As heretofore pointed out, if it is desired to set 100 the train into operation again, the switch 40 will be closed for energizing the magnetron solenoid 17.

Referring now to Figures 4 and 4^a, which show a modified form of my train control system, there is provided, as in the form shown in Figure 2, a brake mechanism 33' in a circuit including the contact 34', the armature 31' and the battery 32', the armature 31' being controlled by the electromagnet of a relay 21', the said relay being connected in 110 the output circuit of the magnetron as by means of the conductor 22' connected to the anode terminal 15' of the magnetron M' and by means of the conductor 23' which is connected to the solenoid 17' surrounding the 115 magnetron tube M' and arranged coaxially and symmetrically with the elements of the magnetron tube, the solenoid 17' being in turn connected to the high tension current battery 25', which in turn is connected by 125 means of the conductor 26' to the cathode terminal 13' of the cathode or filament 11'. Similarly, as in Figure 2, the filament 11' is included in an energizing circuit provided with battery 18', a conductor 19' and a con- 130

ductor 20', conductor 19' being connected to the cathode terminal 13' and the conductor 20' being connected to the cathode terminal 14'. The solenoid 16' is similarly connected 5 in series with a conductor 29', rheostat 30', conductor 31^b, battery 27' and conductor 28'. In the modification shown in Figure 4, however, the circuits of the solenoid 16' and 17' are interrelated as to effect a safe operation 10 of the system at all times responsive to any accidental break in any of the circuits. To this end the circuit of the solenoid 16' is provided with a relay coil 47 controlling the armature 48 in the circuit of the solenoid 15 17', one terminal of the relay coil 47 being connected by means of a conductor 49 to the conductor 31^b, the other terminal of the relay coil 47 being connected by a conductor 50 to the rheostat 30', the armature 48 and a 20 cooperating contact 51 being in turn interposed between the conductor 23' and the solenoid 17' in the circuit of the said solenoid 17'. With this arrangement it will be apparent that upon failure of the circuit of the 25 coil 16' the relay magnet 47 will be deenergized and the circuit of the solenoid 17' will be automatically opened for deenergizing the relay 21' to effect the application of the brakes. It will be furthermore seen 30 that if any of the other circuits accidentally "give way" the brake mechanism of the train will be also set. Thus, if the glow circuit be broken, the magnetron will be extinguished. Thus, also, if the circuit including 35 the solenoid 17' is broken, the magnetization of coil 16' will be predominant, effecting the closing of the magnetron M' which in turn will effect the setting of the brakes. Moreover, it will be seen that if any of the 40 track circuits fail, such as that of the track magnet m, deenergization of the coil 35' thereof will automatically cause the ascent of the magnet core 37 to effect the closing of the magnetron M.

45 As in the form of the system shown in Figure 2, the system shown in Figure 4 is associated with a plurality of track magnets m and m', the magnet m being shown in Figure 4 of the drawings, these magnets having a construction similar to those shown 50 in Figures 1 to 3 of the drawings, the magnet m including, for example, the coil 35', the tube 36', the core 37' and the spring 38'. The magnet m in Figure 4 is shown with the core 37' in the ascended position with the coil 35' deenergized, this effecting a magnetic field active on the magnetron M' of a magnitude such that the magnetization is 55 somewhere on the part of the curve designated as A' B' in Figure 4^a of the drawings as denoted for example by the asterisk (*) shown in said figure, this effecting the closing of the magnetron M' and the deenergizing of the circuit controlled thereby for effecting the release of the armature 31' to

open the braking circuit, as shown in Figure 4 of the drawings.

The train apparatus in this modification is also provided with the energizing or magnetron reopening circuit including the conductor 39', normally open switch 40', resistance 41' and conductor 42'.

The train control system of my invention, in which a train circuit is magnetically influenced by a track mechanism, as shown in Figures 1 to 4 of the drawings, may be modified within wide limits as shown, for example, in the modification disclosed in Figure 5 of the drawings. Referring now to Figure 5 of the drawings, I first provide 75 a thermo-ionic element M² consisting of a vacuous tube 52 provided with a straight filament or cathode 53 and a coaxially and symmetrically arranged anode 54, the cathode being provided with the terminals 55 and 56 and the anode being provided with the terminal 57. The filament or glow circuit includes the battery 58 connected to the cathode terminals 56 and 55 by means of the conductors 59 and 60. The output circuit of the thermo-ionic element M² includes the relay 61, the relay 62, an armature 63 cooperating with a contact 64 and a battery 65, all connected in series across the cathode and anode terminals 55 and 57 respectively, 80 these parts being connected in series by means of conductors 66, 67, 68 and 69 respectively. 85

The thermo-ionic element M² is normally 90 open and the circuit controlled thereby is normally energized for energizing the train control magnet 61. Cooperating with the thermo-ionic element M² there is provided the track magnet m³ having a construction 95 the same as the track magnet m of Figures 1 to 4, the operation of this magnet being such that when the core 70 thereof is in its lower full line position as shown in Figure 5, the thermo-ionic device M² will be uninfluenced in passing thereover and when the core 70 is in its dotted line position as shown in said figure the thermo-ionic element M² is affected by the magnetic field of the core with result that the thermo-ionic element is momentarily closed, deenergizing the relay 100 electromagnet 62 for the release of the armature 63 and the opening of the contact 64, the momentary closing of the thermo-ionic element M² thus effecting the permanent 105 opening of the circuit to the brake control relay 61. Thus, with clear track conditions the thermo-ionic device M² is uninfluenced 110 permitting the train to run clear and under danger and caution conditions when the track magnet m³ is deenergized the train circuit will be opened to effect the application 115 of the brakes. 120

For reopening the thermo-ionic element M² and for reenergizing the train circuit 125 controlled thereby, as under caution train 130

conditions, I further provide a second thermo-ionic element M^3 in the form of a magnetron, the magnetron M^3 including the straight filament or cathode 71 having the 5 terminals 72 and 73 and the symmetrically and coaxially arranged anode 74 having the terminal 75, all included in a vacuous vessel 76 and surrounding the said vessel symmetrically with the elements of the thermo-ionic device there is provided the solenoid or coil 77. The closed circuit of the filament 71 includes the battery 78 connected to the terminals 72 and 73 as by means of the conductors 79 and 80 respectively. The sole- 10 noid 77 is energized by means of a battery 81 connected to the terminals of the solenoid by means of the conductors 82 and 83 respectively, a rheostat 84 being arranged in this circuit and adjusted so that sufficient 15 current will pass through the solenoid 77 to produce a magnetic field of a quantity or magnitude sufficient to normally close the magnetron M^3 .

The output circuit of the magnetron M^3 20 is arranged to control the relay magnet 62 of the circuit of the element M^2 and to this end one terminal of the relay is connected by means of a conductor 85 to a battery 86, which in turn is connected by means of a 25 conductor 87 to the cathode terminal 73, the other terminal of the relay magnet 62 being connected as by means of the conductor 88 to the anode terminal 75 of the magnetron M^3 . With this arrangement and with the 30 magnetron M^3 normally closed the circuit to the relay magnet 62 is normally open, the relay magnet 62 being only energized normally by the activity of the magnetron M^2 .

For reopening the element M^2 after it has 35 been closed by the magnet m^3 I provide the second track magnet m^4 having a construction similar to the track magnet m' of Figures 1 to 4, the track magnet m^4 being adapted for controlling the operation of the magnetron M^3 . The polarity of the track magnet m^4 is such as to oppose or neutralize 40 the magnetic field of the magnetron solenoid 77 so that upon passage of the magnetron M^3 over the track magnet m^4 the resultant 45 magnetic field active on the magnetron M^3 will be insufficient to retain the same closed and under such conditions the magnetron M^3 will be opened. The opening of the magnetron M^3 will close the circuit including 50 the relay magnet 62, closing of this circuit effecting the energization of said magnet and the attraction of the armature 63, this in turn effecting the closing of the circuit to the thermo-ionic element M^2 , the closing 55 of this circuit reopening the said thermo-ionic element M^2 . Although the action of the track magnet m^4 on the magnetron M^3 is only momentary, the momentary opening of the magnetron M^3 will be sufficient to 60 energize the relay magnet 62 and continued en-

ergization of the relay magnet 62 will be effected by the reopening of the thermo-ionic device M^2 , permanent reopening of the device being thus obtained.

The track operating conditions for the 70 system shown in Figure 5 are the same as for the system shown in Figures 1 to 4, the track magnets being operated in the same manner to obtain the same train indications. Thus, for the train running clear the magnet 75 m^3 is energized and the magnet m^4 deenergized so that the cores 70 and 89 assume their full line positions as shown in Figure 5, both the thermo-ionic elements M^2 and M^3 being uninfluenced with the magnets so 80 operated, the train indications being unmodified in passing the track magnets. However, under caution conditions the track magnet m^3 is deenergized and the track magnet m^4 is energized, the cores 70 and 89 assuming the upper dotted line positions as 85 shown in Figure 5, the magnetron M^2 being closed by the influence of the core 70 and the magnetron M^3 being opened by the influence of the core 89 to cause the reopening 90 of the thermo-ionic device M^2 . With danger track conditions ahead both track magnets m^3 and m^4 are deenergized, the core 70 of the track magnet m^3 assuming the upper dotted line position and the core 89 of track magnet m^4 assuming its descended position and with this arrangement the thermo-ionic device M^2 will be closed and will not be 95 relit by the magnetron M^3 , effecting a complete stopping of the train. After the complete stopping of the train the thermo-ionic device M^2 may again be set into activity and to this end there is provided the shunt circuit comprising a normally open switch 100 105 105 and a resistance 91 connected to the conductors 87 and 88 by means of the conductors 92 and 93. Upon closing of the normally open switch 90 it will be evident that the relay magnet 62 will be energized to close the circuit of the thermo-ionic device M^2 , 110 causing reopening of the same.

Although the thermo-ionic device M^2 has been shown in this last form of my invention to comprise an ordinary thermo-ionic device magnetically influenced by roadside mechanism, it will be apparent that I may here provide the thermo-ionic element M^2 with a solenoid circuit so arranged that a magnetic field is normally effective on the thermo-ionic element M^2 of a magnitude insufficient, however, to close the same, but of a magnitude close to the critical point of the magnetron so that upon passage of the thermo-ionic device M^2 over a track magnet m^3 115 a small amount of magnetization alone will 120 be sufficient to cause the closing of the thermo-ionic element M^2 , a very sensitive operation being thereby effected.

The use, installation and operation of my 130 novel train control system will be fully ap-

parent from the above detailed description of the construction and operation thereof. It will be further apparent that in each instance I have provided a train circuit or circuits directly and magnetically influenced by track mechanism to cause a sudden inertialess change in the train mechanism responsive to changing track conditions. The advantages in my system for train control are tremendous in that in the first place there is no inertia in the magnetron closing process so that an instant of passage over the track magnet is sufficient to produce the desired result and in the second place, the system is so sensitive that a track magnet of small dimensions is sufficient to influence the train circuits to effect the closing of the magnetron, this train control system being thus especially adaptable for controlling the ordinary fast moving train.

While I have shown my device in the preferred forms, it will be obvious that many changes and modifications may be made in the structure disclosed, without departing 25 from the spirit of the invention, defined in the following claims.

I claim:

1. In combination, a vehicle circuit including an electron discharge device of 30 which a magnetic field is a controlling component, roadside mechanism including means for influencing the said device to vary its activity and means active for maintaining such activity when the said device is so influenced.

2. In combination, a vehicle circuit including an energized electron discharge device of which a magnetic field is a controlling component, roadside mechanism for influencing the said device to deenergize the same, and means active for maintaining the said device deenergized when so influenced.

3. In combination, a vehicle circuit including an electron discharge device of 45 which a magnetic field is a controlling component, roadside mechanism including means for momentarily influencing the said device as the vehicle moves over the roadbed to vary its activity and means active for maintaining such varied activity when the said device is so influenced.

4. In combination, a vehicle circuit including an electron discharge device of which a magnetic field is a controlling component, roadside mechanism including means for 50 momentarily influencing the said device as the vehicle moves over the roadbed to vary its activity and means active for maintaining such activity when the said device is so influenced.

5. In combination, a vehicle circuit including a magnetron of which a magnetic field is a controlling component, roadside mechanism including means for influencing 55 the magnetron to vary its activity and means

active for maintaining such activity when the magnetron is so influenced.

6. In combination, a vehicle circuit including an electron discharge device of 70 which a magnetic field is a controlling component, said electron discharge device being capable of being deenergized, roadside mechanism for influencing the said device to energize the same and means for maintaining the said device energized when so influenced. 75

7. In combination, a vehicle circuit including an electron discharge device of 80 which a magnetic field is a controlling component, said electron discharge device being capable of being deenergized, roadside mechanism for momentarily influencing the said device to energize the same and vehicle carried means for maintaining the said device energized when so momentarily influenced.

8. In combination, vehicle carried mechanism including a controlled circuit, a single 85 electron discharge device of which a magnetic field is a controlling component governing said circuit, and means including roadside mechanism for influencing the said electron discharge device to selectively produce a persisting energized or deenergized condition in said controlled circuit.

9. In combination, vehicle carried mechanism including a controlled circuit, a single 90 electron discharge device of which a magnetic field is a controlling component governing said circuit, and means including roadside mechanism for momentarily influencing the said electron discharge device to selectively produce a persisting energized or deenergized condition in said controlled circuit.

10. In combination, a vehicle carried 105 mechanism comprising an electron discharge device of which a magnetic field is a controlling component, an electrode circuit for said device and roadside mechanism for influencing said device to impose a sustained energized condition in said electrode circuit.

11. In a train control mechanism, a controlled circuit, a single electron discharge 110 device of which a magnetic field is a controlling component governing said circuit and means for magnetically influencing said electron discharge device to produce selectively in said controlled circuit a persisting energized or deenergized state. 115

12. In a train control mechanism, a controlled circuit, a single electron discharge 120 device of which a magnetic field is a controlling component governing said circuit and means for magnetically influencing said electron discharge device momentarily to produce selectively in said controlled circuit a persisting energized or deenergized state. 125

13. In a train control system, a controlled 130 circuit, a single electron discharge device of

- 8.
- which a magnetic field is a controlling component governing said circuit, said device being capable of being deenergized, means for magnetically influencing said device to energize the same and means for maintaining said device energized when so influenced.
14. In a train control system, a controlled circuit, a single electron discharge device of which a magnetic field is a controlling component governing said circuit, said device being capable of being energized, means for magnetically influencing the said device to deenergize the same and means for maintaining said device deenergized when so influenced.
15. In a vehicle control system, a vehicle circuit, and a magnetron for controlling the same, the said magnetron including opposed magnetic fields.
16. In a vehicle control system, a vehicle circuit, a magnetron for controlling the same, the said magnetron including a solenoid effective for establishing a given activity of the magnetron and a second solenoid in said circuit for opposing the influence of the first solenoid.
17. In a vehicle control system, a vehicle circuit, a magnetron for controlling the same, the said magnetron including a magnetic field producing means effective for establishing a given activity of the magnetron and a solenoid in said circuit for opposing the influence of the magnetic field.
18. In a vehicle control system, a vehicle circuit, a magnetron for controlling the same, the said magnetron including means for establishing opposed magnetic fields having a resultant magnitude to permit activity of the magnetron and means for modifying the resultant of said fields for deenergizing the magnetron.
19. In a vehicle control system, a vehicle circuit, a magnetron for controlling the same, the said magnetron including means for establishing opposed magnetic fields having a resultant magnitude to permit activity of the magnetron and roadside magnetic means for modifying the resultant of said fields for deenergizing the magnetron.
20. In combination, a vehicle circuit including an electron discharge device of which a magnetic field is a controlling component active for impressing a given characteristic on said circuit, roadside mechanism for influencing the said device to change the characteristic of said circuit and means including additional roadside mechanism for reestablishing the said given characteristic of the circuit.
21. In combination, a vehicle circuit including an electron discharge device of which a magnetic field is a controlling component active for impressing a given characteristic on said circuit, roadside mecha-
- nism for magnetically influencing the said device to change the characteristic of said circuit and additional roadside mechanism for influencing the said device for reestablishing the said given characteristic of the circuit.
22. In combination, a vehicle circuit including an electron discharge device of which a magnetic field is a controlling component active for normally energizing the circuit, roadside mechanism intermittently and magnetically active on the said device for closing the same to deenergize the circuit and means for reopening the said device for reenergizing the circuit.
23. In combination, a vehicle circuit including an electron discharge device of which a magnetic field is a controlling component active for normally energizing the circuit, roadside mechanism intermittently and magnetically active on the said device for closing the same to deenergize the circuit and additional roadside mechanism for reopening the said device for reenergizing the circuit.
24. In combination, a vehicle circuit including a magnetron and roadside mechanism for controlling the activity of the magnetron including means for closing the same and means for reopening the same.
25. In combination, a vehicle circuit including an electron discharge device of which a magnetic field is a controlling component, roadside mechanism for magnetically influencing the said device to change the characteristic of the circuit, means for maintaining the circuit changed after the device is so influenced and means including additional roadside mechanism for re-establishing the original characteristic of the circuit.
26. In combination, a vehicle circuit including an energized electron discharge device of which a magnetic field is a controlling component, roadside mechanism for influencing the said device to open the said circuit, means for maintaining the circuit opened after the device has been so influenced and means for reenergizing the said device.
27. In combination, a vehicle circuit including an energized electron discharge device of which a magnetic field is a controlling component, roadside mechanism for influencing the said device to open the said circuit, means for maintaining the circuit opened after the device has been so influenced and means including additional roadside mechanism for reenergizing the said device.
28. In combination, a vehicle circuit including an electron discharge device of which a magnetic field is a controlling component controlling the same, means for influencing the said device to impose a sus-

- tained characteristic on said circuit, said means including roadside mechanism momentarily influencing the device in the movement of the vehicle and means for modifying the said influence. 5
29. In a vehicle control system, a vehicle circuit, a magnetron for controlling the same, the said magnetron including opposed magnetic fields having a given magnitude and roadside mechanism for changing and re-establishing the said magnitude. 10
30. In a vehicle control system, a vehicle circuit, a magnetron for controlling the same, said magnetron including a solenoid effective for establishing a given activity of the magnetron and a second solenoid in said circuit for normally opposing the influence of the first solenoid and roadside mechanism for first aiding the activity of the first solenoid and then aiding the activity of the second solenoid. 15
31. In a vehicle control system, a vehicle circuit, a magnetron for controlling the same, the said magnetron including means for establishing opposed magnetic fields having a resultant magnitude to permit activity of the magnetron, roadside mechanism for modifying the resultant of said fields for deenergizing the magnetron and additional roadside mechanism for reestablishing said resultant magnitude for reenergizing the magnetron. 20
32. In combination, a vehicle circuit including a normally open electron discharge device of which a magnetic field is a controlling component and means for permanently closing the same including roadside mechanism momentarily operative magnetically on the device in the passage of the vehicle. 25
- 40 33. In combination, vehicle mechanism and roadside mechanism for magnetically influencing the same, the said roadside mechanism including spaced magnets selectively operable for influencing the train mechanism in opposite manners, the said spaced magnets each comprising a movable magnet core. 35
34. In combination, vehicle mechanism and roadside mechanism for magnetically influencing the same, the said roadside mechanism including spaced magnets selectively operable for influencing the train mechanism in opposite manners, each of the said track magnets comprising a magnet coil and a magnet core slidably mounted therein. 45
- 50 35. In combination, vehicle mechanism and roadside mechanism for magnetically influencing the same, the said roadside mechanism including spaced magnets selectively operable for influencing the train mechanism in opposite manners, each of the said track magnets comprising permanent magnet cores hermetically enclosed in a casing and movable in the casing. 55
- 60 36. In a system of the class described, track mechanism comprising spaced magnets each provided with a coil and a permanent magnet slidably movable therein. 65
37. In a railway signaling system, a vehicle carried mechanism comprising an electron discharge tube, a circuit including a source of current and said tube, a signal controlled by said circuit, a magnet for opposing the flow of current through said tube, a winding for opposing the effect of said magnet on the flow of current through said tube, and train control means for supplying current to said winding. 70
38. In a railway signaling system, a vehicle carried mechanism comprising an electron discharge tube having a plate and a heated filament, a circuit including a source of current and the plate and filament of said tube, a signal controlled by said circuit, a magnet for opposing the flow of current through said tube, a winding for opposing the effect of said magnet on the flow of current through said tube, and train control means for supplying current to said winding. 75
39. In a train control system, vehicle carried mechanism comprising a vehicle circuit including a magnetron of which a magnetic field is a controlling component, roadside mechanism including means for influencing the magnetron to vary its activity and means active for maintaining such activity when the magnetron is so influenced. 80
40. In a train control system, vehicle carried mechanism including a controlled circuit, a single electron discharge device of which a magnetic field is a controlling component governing said circuit, and means including roadside mechanism for momentarily influencing the said electron discharge device to selectively produce a persisting energized or deenergized condition in said controlled circuit. 85
41. In a train control system, a vehicle circuit including an energized electron discharge device of which a magnetic field is a controlling component, roadside mechanism for influencing the said device to open the said circuit, means for maintaining the circuit opened after the device has been so influenced and means for reenergizing the said device. 90
42. In a train control system, a vehicle circuit including an energized electron discharge device of which a magnetic field is a controlling component, roadside mechanism for influencing the said device to open the said circuit, means for maintaining the circuit opened after the device has been so influenced and means including additional roadside mechanism for reenergizing the said device. 95
